(57) **CLAIM**

The ornamental design for a wake-up light, as shown and described.

DESCRIPTION

FIG. 1 is a front elevational view of a wake-up light showing my new design;

FIG. 2 is a rear elevational thereof;

FIG. 3 is a left side elevational view thereof;

FIG. 4 is a right side elevational view thereof;

FIG. 5 is a top plan view thereof;

FIG. 6 is a bottom plane view thereof;

FIG. 7 is a perspective view thereof showing the front and right sides; and,

FIG. 8 is a perspective view thereof showing the rear and left sides.

The broken lines in the drawings depict parts of the wake-up light that form no part of the claimed design.

1 Claim, 8 Drawing Sheets
